UNITED STATES PATENT OFFICE.

CLYDE J. COLEMAN, OF NEW YORK, N. Y.

RAILWAY TRAFFIC-CONTROLLING APPARATUS.

No. 822,508.

Specification of Letters Patent.

Patented June 5, 1906.

Application filed December 4, 1905. Serial No. 290,085.

To all whom it may concern:

Be it known that I, CLYDE J. COLEMAN, a citizen of the United States, residing in the borough of Manhattan, city of New York, in 5 the county of New York and State of New York, have invented certain new and useful Improvements in Railway Traffic-Controlling Apparatus, of which the following is a specification, reference being had therein to 10 the accompanying drawing, forming a part thereof.

My invention relates, broadly, to railway traffic-controlling apparatus, and that particular embodiment of my invention which I 15 have particularly described hereinafter and which is illustrated in the accompanying drawing belongs to that class of railway traffic-controlling apparatus known as normal "danger," "home," and "distant" railway 20 way signaling apparatus which operates to control railway traffic on a railway-line by the display of visual signals, such as semaphore signals.

Reliability of operation and simplicity and 25 economy of construction and maintenance are the broad objects of my invention.

It is a more specific object of my invention to provide means whereby two different traffic-controlling apparatuses located at different 30 points on a railway-line may be reliably and simultaneously controlled through one common traffic-controlling circuit extending from one traffic-controlling apparatus to the other.

To this end my invention comprises a traffic-controlling circuit and means for supplying the circuit with a composite electric current including a given current component distinguished by some current characteristics—such, for instance, as a given periodic variation—the traffic-controlling circuit being arranged to extend from one traffic-controlling apparatus located on the railway-line to another traffic-controlling apparatus 45 located at a different point on the railway-line and such circuit controlling both such traffic-controlling apparatuses, one of such traffic-controlling apparatuses being controllable by the given current component, distinguished in some instances by a periodic variation, and the other traffic-controlling apparatus being controllable by another component of the composite current.

With regard to more specific details, it may 50 be stated that it is an object of my invention to provide means whereby one common con-

trolling-circuit—for instance, a rail-circuit including the traffic-rails of a railway-track—may be reliably employed simultaneously to govern a traffic-controlling or signaling apparatus at the advance end of the circuit subject to control of a train in rear of such apparatus and to govern a traffic-controlling or signaling apparatus at the rear end of the circuit subject to control of a train 65 in advance of such apparatus.

In the illustrated embodiment of my invention the last-mentioned object is attained in a normal danger, home, and distant railway block-signaling system wherein the traffic-rails of a given signaling-block are employed as conductors of a composite current in the common controlling-circuit above mentioned, the signaling apparatus at the advance end of the block being controlled or cleared by a 70 current component having a given periodic variation and subject to presence of a train in rear of the block, while at the same time the signaling apparatus at the rear end of the block is governed by another component 75 of the same composite current subject to control of a train in advance of such rear signaling apparatus and which may be in advance of the block.

In my invention a given component of the 80 composite current which is characterized by a given periodic variation may consist in an alternating-current component, as in the specific instance illustrated, while another component or components of the composite 85 current are distinguished from the given component by some current characteristic differing from the particular periodic variation of such given component, such other component being in the specific instance 90 illustrated a substantially uniform current 95 having no periodic variation at all.

In the illustrated embodiment of my invention the source of that current component which governs a traffic-controlling apparatus 100 controlled by presence of a train in rear thereof is located at the rear end of the railway block or section through which the composite current flows, while the source of the current components which govern a traffic-controlling apparatus controllable by presence of 105 trains in advance is located at the advance end of such railway block or section, and in this particular embodiment such current component governing a traffic-controlling apparatus controllable from in rear is a component 110 having a periodic variation, while the

components governing a traffic-controlling apparatus controllable by a train in advance are unidirectional-current components.

One particular object of my invention is to govern a given traffic-controlling apparatus located on a railway-line from a point of control on the railway-line in rear of such given traffic-controlling apparatus—for instance, more specifically, to automatically clear a railway-signal by presence of a railway-train approaching the signal from in rear thereof. To this end my invention comprises, broadly, a traffic-controlling or signaling apparatus located on a railway-line and normally in blocking or danger-indicating condition and controllable by an electric current characterized by a periodic variation, an electric circuit in control of such apparatus and including the traffic-rails of the railway extending in rear thereof, means for supplying to the controlling-circuit an electric current characterized by a periodic variation—such, for instance, as a periodic alternation—and means controlling such electric current by approach of a train toward the traffic-controlling or signaling apparatus to actuate or control such apparatus or move it into unblocking or clear position. When the controlling-circuit is employed to transmit or is subjected to the influence of some additional electric current or current component other than that employed to effect a given operation of the traffic-controlling apparatus from a point in rear thereof, my invention then broadly comprehends a traffic-controlling or signaling apparatus located on a railway-line and in a given unblocking or clearing operation selectively controllable by a given current or current component, distinguished from the additional current by a given current characteristic which may consist in a given periodic variation, and which given current component flows in an electric circuit in control of the traffic-controlling or signaling apparatus and extending in rear thereof along the line of traffic, and means for controlling the given current or current component from a point in rear of the apparatus to control such apparatus.

In the illustrated embodiment of my invention the given current component which effects control of the traffic-controlling apparatus from a point in rear is an alternating current, and in this particular embodiment the source of such current is located at the rear end of the traffic-controlling electric circuit, which location has some very considerable advantages. Also in the illustrated instance the additional electric current or current component not employed to effect the given operation of the traffic-controlling or signaling apparatus is employed to effect another operation thereof and is also employed to control a second traffic-controlling or signaling apparatus at the rear end of the controlling-circuit. This use of the additional

current component, however, is only incidental to this particular embodiment of that feature of my invention whereby some particular operation of a traffic-controlling or signaling apparatus is effected from a point of control in rear by selective responsiveness to some particular current component in lieu of or in discrimination against some other current component.

The accompanying drawing is a diagrammatic representation of a portion of a single railway-track equipped with a normal danger home and distant railway block-signaling system embodying my invention.

The diagram shows three successive railway signalizing apparatuses A, B, and C, located substantially at the termini of successive signalizing blocks or sections of the railway-line.

The signalizing apparatus is the same at each of the signalizing-stations A, B, and C, and a brief description of the signalizing apparatus A will therefore be representative of the apparatus of the system generally.

Each signalizing apparatus comprises home and distant signal semaphores, such as the semaphores 2^a and 4^a of the signalizing apparatus A, mounted upon a suitable signal-post, such as 6^a. (Indicated in dotted lines.)

The diagram shows separate signal-clearing motors 3^a and 5^a, arranged to clear the home and distant signal semaphores, respectively, the motors being represented as though connected with the semaphore-blades by pull-cords adapted to move the blades into clear positions. It will of course be understood that this arrangement of signal-semaphores and individual motors is only a diagrammatic representation intended to symbolize any means whereby the respective signal-semaphores may be moved to clear positions by passage of current in the local signal-clearing circuits in which their respective diagrammatic motors are included and whereby either signal-semaphore may be returned to danger position by failure of current in its respective local signal-clearing circuit.

The diagram represents a pole-changing switch including two contact-levers 9^a and 10^a, combined with a distant-signal-circuit-closing contact-lever 11^a, the three contact-levers being mounted upon pivots arranged in alinement and being connected by a common insulating-link 12^a. This combined pole-changing and distant-signal-circuit-closing switch is arranged to be actuated by movement of the home-signal semaphore 2^a, such arrangement being diagrammatically represented in the drawing by a rod 7^a, depending from a pivotal connection with the home-signal semaphore and at its lower end carrying an insulated horizontally-extending foot 8^a, co-operating with two projections or fingers forming portions of the contact-levers

9^a and 10^a, which portions project from the pivotal centers of such contact-levers opposite their pole-changing portions or fingers.

The disposition of the foregoing parts is such that when the home-signal semaphore reaches its clear position the pole-changer-actuating foot 8^a will engage the upper contact-lever 9^a to throw the pole-changer into position for clearing the distant signal of the signaling apparatus in rear, while at the same time throwing the contact-lever 11^a into position for partially closing the local clearing-circuit of the distant-signal semaphore 4^a.

Each signaling apparatus comprises an alternating-current relay, which may be constructed in any suitable manner, but which is represented in the diagram as including a magnetic core, such as 17^a, surrounded by an energizing-coil 24^a and projecting upwardly through a conductive loop or ring 18^a, mounted upon the insulating-arm 19^a of a pivoted lever, including also a contact-finger 20^a. The insulating-arm and contact-finger 19^a and 20^a extend horizontally from opposite sides of the pivotal center of the lever, the insulating-arm, with its conductive ring, being considerably heavier than the contact-finger, so that such insulating-arm will always tend to fall and raise the contact-finger out of contact with its coöperating contact-stop 21^a. When an alternating current is caused to circulate through the energizing-coil 24^a, the core 17^a is subjected to an alternating magnetic flux, which develops within the conductive ring 18^a an alternating current circulating about the axis of the core, but having a phase lag of more than ninety degrees behind the inducing magnetic flux, whereby the mean reaction between such flux and the induced current is rendered repulsive, so as to repel the conductive ring 18^a from the core 17^a, thus raising the insulating-arm 19^a and depressing the contact-finger 20^a into contact with its coöperating contact-stop 21^a.

Each signaling apparatus comprises also an advance clearing compound relay including opposed relay-magnets 25^a and 30^a, with contact-fingers 26^a and 28^a, controlled by an armature interposed between the magnets. This armature is unbiased—that is to say, it has no normal bent toward either of the opposed magnets by gravity or by spring adjustment, but merely moves in the direction of preponderating magnetic attraction exerted by either relay-magnet. This armature is not shown, since the construction of such compound unbiased relays is well known in the signaling art.

Each signaling apparatus also includes a home and distant clearing rear track-relay, such as the relay 32^a, controlling two contact-fingers 33^a and 35^a. The contact-finger 33^a is operated by a non-polarized armature, which is attracted by the relay when energized by current in either direction, and

it when so attracted moves its contact-finger 33^a to close the local clearing-circuit of the home-signal semaphore 2^a. The contact-finger 35^a is operated by a polarized armature which is actuated by the relay only when such relay is energized with current in a given direction, which may be designated as the "distant clearing direction," and such contact-finger 35^a when thus operated by its polarized armature completes the local clearing-circuit of the distant-signal-semaphore motor 5^a.

Each signaling apparatus includes also a rotary converter, diagrammatically represented as including a direct-current-motor 80 armature 37^a and an alternating-current-generator armature 38^a.

In describing the operation of the system represented in the diagram each signaling-block will be designated by the reference characters employed to designate the signaling-apparatuses at the ends of the block. The diagram represents the various devices of the signaling apparatuses A, B, and C in their positions and condition such as would be effected by presence of a train, as represented at T in the block in rear of the signaling apparatus A, providing that the signaling-blocks A B and B C were both clear of trains. In describing the sequence of actions of the signaling system as effected by progressive movement of a train along the railway-line it may be assumed that the train T, represented in the block in rear of the signaling apparatus A, has entered such block from a siding in lieu of entering the block from the signaling-block next in rear, this assumption being made simply in order that a clear comprehension of the operation of the system may not depend upon an understanding of any operation of the signaling apparatus which is not shown on the diagram, but which is located at the rear end of the block in rear of the signaling apparatus A.

Before the train T enters the block in rear of the signaling apparatus A the home and the distant signal semaphores of the signaling apparatus A, B, and C are all in danger positions, and the shunt-coils, such as 30^a, of the compound advance clearing-relays preponderate over the series coils, such as 25^a, of such relays, so that all the contacts, such as 26^a 27^a and 28^a 29^a, of such relays are open. All the alternating-current advance clearing-relays, such as 24^a, are also normally deenergized, and their contacts, such as 20^a 21^a, are therefore normally open. All the semaphore-actuated pole-changers are normally in their positions effected by danger positions of the home-signal semaphores, so that the 125 pole-changing contacts, such as 9^a 13^a and 10^a 14^a, are normally closed, while the semaphore-actuated contacts, such as 11^a 16^a, included in the local clearing-circuits of the distant-signal semaphores, are normally open. 130

All the rear track-relays, such as 32^a, are normally energized by current transmitted in home clearing direction through the rail-circuits in advance of such relays, so that the 5 home clearing-contacts, such as 33^a 34^a of such relays are normally closed, while their distant clearing-contacts, such as 35^a 36^a, are normally open.

Before the train enters the block in rear of 10 the signaling apparatus A the series and shunt coils 25^a and 30^a, respectively, of the compound advance clearing-relay at the advance end of such block are energized through the following circuit and circuit branches: 15 from one pole of the advance track-battery 22^a of the signaling apparatus A—for instance, the positive pole thereof—through the conductor 47^a, semaphore-actuated pole-changer contacts 9^a 13^a, and conductor 43^a to 20 one terminal of the shunt-coils 30^a and also to the advance end of the left rail L of the block, and from the conductor 43^a the circuit divides in two branches, one branch leading through the coils of the shunt-relay 30^a to the 25 conductor 44^a and the other branch leading rearward through the left rail L to the rear end of the block, and thence through the coils of the rear track-relay at the rear end of the block to the right rail R of the block, and 30 thence forward through such right rail to the conductor 44^a, wherein the two branches of the circuit reunite, and thence through such conductor 44^a, series coils 25^a of the advance clearing-relay, conductor 46^a, contacts 14^a 35 10^a, and conductor 48^a back to the opposite or negative pole of the advance track-battery 22^a, and until the train enters the block in rear of the signaling apparatus A the relative apportionment of resistances in the series 40 coils 25^a, shunt-coils 30^a, and rail-circuit branch in parallel with the shunt-coils is such that the magnetic attraction of the shunt-coils considerably preponderates over the magnetic attraction of the series coils upon their common unbiased armature, so that the contacts 26^a 27^a and 28^a 29^a are open.

When under the foregoing conditions the train T enters the block in rear of the signaling apparatus A, the home and distant signals at the rear end of such block immediately assume danger positions, while the distant-signal semaphore at the rear end of the block-section in rear of the signaling apparatus A also assumes danger position, these 55 movements of the signals in rear of the train T being effected in a manner which will soon be apparent from the following description of the effects of the presence of the train in the blocks A B and B.C. Also when under the 60 foregoing conditions the train T enters the block in rear of the signals A the rails L R thereof are immediately short-circuited, so as to reduce the resistance of the rail-circuit in parallel with the shunt-coils 30^a of the advance clearing compound relay, and thereby

greatly reduce the amount of current flowing through such shunt-coils, while at the same time greatly increasing the amount of current flowing through the series coils 25^a of such relay, since such series coils are directly 70 in series with the rail-circuit wherein the reduction of resistance is effected. Thereupon the series coils 25^a might preponderate in magnetic attraction upon the unbiased armature of the relay, so as to immediately close 75 its contacts 26^a 27^a and 28^a 29^a. Closure of the contacts 26^a 27^a immediately completes the local clearing-circuit of the home-signal semaphore 2^a, which local circuit is as follows: from one pole of the local battery 31^a through 80 the conductor 49^a, normally closed home-clearing rear-track-relay contacts 33^a 34^a, conductor 54^a, contacts 26^a 27^a, conductor 53^a, conductor 52^a, home-signal-clearing motor 3^a, and conductor 51^a back to the opposite pole of the local battery 31^a. Immediately upon completion of the foregoing local home clearing-circuit the home-signal semaphore 2^a commences its movement to clear position. 90

Closure of the contacts 28^a 29^a of the advance clearing-relay completes the local circuit of the motor-armature 37^a of the rotary converter, such local circuit being as follows: from one pole of the local battery 31^a through 95 the conductor 49^a, contacts 29^a 28^a, conductor 50^a, motor-armature 37^a, and conductor 51^a back to the opposite pole of the local battery 31^a. Thereupon the rotary converter is immediately started and its alternating-current-generator armature 38^a commences to 100 deliver alternating current to the signaling apparatus B through the following circuit: from one terminal or brush of the alternating-current-generator armature 38^a through the 105 conductor 42^a, condenser 39^a, conductor 40^a, left rail L^a of the block A B, conductor 43^b, condenser 23^b, conductor 45^b, coil 24^b of the alternating-current advance clearing-relay, conductor 44^b, right rail R^b rearward to the 110 conductor 41^a, and thence through such conductor to the opposite brush or terminal of the alternating-current-generator armature 38^a. It will be noted that the alternating-current advance clearing-relay 24^b is included 115 in the foregoing circuit by being bridged across the advance ends of the track-rails L^a R^b in series with the condenser 23^b, which is of such capacity as to freely admit alternating current through the relay 24^b, while at the same time such condenser effectually prevents flow of unidirectional current from the advance track-battery 22^b through the alternating-current relay 24^b, thereby avoiding 120 any waste of battery-current which might occur if such current were free to flow through the alternating-current relay. The condenser 39^a, likewise in series with the alternating-current-generator armature 38^a, bridged across the rails L^a R^b at the rear end of the 125 130

block, similarly permits transmission of alternating current through the circuit which has just been traced, while at the same time preventing wasteful flow of battery-current through the generator-armature. Current in the foregoing rail-circuit of the block A B energizes its alternating-current advance clearing-relay 24^b, so as to close the contacts 20^b 21^b thereof, and thus complete the local clearing-circuit of the home-signal semaphore 2^b, such local clearing-circuit being as follows: from one pole of the local battery 31^b through the conductor 49^b, home clearing-contacts 33^b 34^b, closed by current flowing 15 in home clearing direction through the rear track-relay 32^b, and from the contact 34^b through the conductor 54^b, contacts 21^b 20^b, conductor 52^b, home-signal clearing-motor 3^b, and conductor 51^b back to the opposite 20 pole of the local battery 31^b. Such current through the motor 3^b operates the motor to clear the home-signal semaphore 2^b, which when it reaches clear position reverses its semaphore-actuated pole-changer, while at 25 the same time closing its semaphore-actuated contacts 11^b 16^b, included in the local clearing-circuit for the distant-signal semaphore 4^b. As the semaphore-actuated pole-changer of the signaling apparatus B is reversed the 30 circuit of the advance track-battery 22^b through the rear track-relay 32^a at the rear end of the block A B is of course momentarily broken, so that such rear track-relay 32^a is momentarily deenergized and momentarily 35 opens its contacts 33^a 34^a, thus momentarily opening the local clearing-circuit of the home signal 2^a; but by the employment of a slow-acting semaphore-retaining clutch or other means well known to the art the home-signal 40 semaphore 2^a is retained in its clear position during the momentary break in its local clearing-circuit, such local home clearing-circuit being immediately reclosed at its contacts 33^a 34^a by reenergization of the rear track- 45 relay 32^a by current transmitted in distant clearing direction from the advance track-battery 22^b as soon as the semaphore-actuated pole-changer of the signaling apparatus B reaches its reversed position. 50 As soon as current in the distant clearing direction is established in the rail-circuit of the block A B and in the rear track-relay 32^a thereof the distant clearing-contacts 35^a 36^a of such relay are closed to close the local clearing-circuit of the distant-signal semaphore 4^a, such local clearing-circuit being as follows: from one pole of the local battery 31^a through the conductor 49^a, contacts 33^a 34^a, conductor 54^a contacts 26^a 27^a, conductor 53^a, conductor 52^a, semaphore-actuated contacts 11^a 16^a, already closed by clearing of the home-signal semaphore 2^a, and from the contact 16^a through the conductor 55^a, distant-signal-clearing motor 5^a, conductor 56^a, contacts 36^a 35^a, and conductor 51^a back to the opposite site pole of the local battery 31^a. Current in the foregoing local distant-signal-clearing circuit actuates its clearing-motor 5^a to clear the distant-signal semaphore 4^a. The train now proceeds by the cleared home and distant signals of the apparatus A and enters the rear end of the block A B, thereby immediately short-circuiting the rails L² R² of such block, so as to cut off the transmission of clearing-current from the track-battery 22^b at the 70 advance end of the block rearward to the rear track-relay 32^a of the signaling apparatus A. Thus such rear track-relay is immediately deenergized and immediately opens both its home clearing and its distant clearing contacts, so as to open the local home clearing and distant clearing local circuits and cause the home and distant signals 2^a and 4^a to assume danger positions. The short-circuiting effect of the train in the 75 block A B also immediately cuts off the transmission of alternating current from the generator-armature 38^a of the signaling apparatus A forward through the rail-circuit of the block to the alternating-current advance 80 clearing-relay 24^b of the signaling apparatus B, whereupon such alternating-current relay immediately opens its contacts 20^b 21^b, so as to momentarily open the local clearing-circuit of the home-signal semaphore 2^b, such 85 local clearing-circuit being, however, reclosed before its home-signal semaphore can assume danger position by closure of the contacts 26^b 27^b of the compound advance clearing-relay due to preponderance of its series coils 90 25^b, effected by presence of the train in the block A B, for reasons already pointed out with respect to the corresponding action of the compound clearing-relay of the signaling apparatus A. Such preponderance of the 95 series coils 25^b over the shunt-coils 30^b also simultaneously closes the contacts 28^b 29^b to complete the local circuit of the motor-armature 37^b of the rotary converter of the block B C, so as to immediately commence transmission of alternating clearing-current forward through such block to the alternating-current advance clearing-relay 24^c of the signaling apparatus C. Such current in the 100 clearing-relay 24^c effects clearing of the home-signal semaphore 2^c, so as to reverse its semaphore-actuated pole-changer and establish distant clearing-current in the block B C to clear the distant-signal semaphore 4^b at the rear end thereof, all in the manner hereinbefore set forth with regard to the corresponding clearing operations of the home-signal semaphore 2^b and the distant-signal semaphore 4^a. The train then proceeds into the block B C, causing the home and distant signals 2^b and 4^b at the rear end thereof to assume danger positions and clearing the home-signal in advance of the signaling apparatus C, so as to clear the distant signal 4^c of such apparatus. Thus the train proceeds along 110 115 120 125 130

the railway-line, clearing all the signals in advance as it approaches them, it being understood, of course, that the clearing of each signal is dependent upon a clear condition of the block which the signal represents—that is to say, the clearing of each home signal is dependent upon clear condition of the block immediately in advance thereof, and the clearing of each distant signal is dependent upon the clear condition of the block second in advance thereof.

It will be noted that when a train has entered a given signaling-block; so as to establish alternating-clearing current in the block next in advance thereof, the rail-circuit of such block next in advance is supplied with a composite electric current, which in the present instance comprises one unidirectional uniform current component delivered by the advance-track battery, while the other component is characterized by a periodic variation and is in the present instance an alternating-current component delivered by the generator-armature at the rear end of the rail-circuit. The rear track-relays are selectively responsive to the unidirectional uniform current component—that is to say, they respond to this current component and do not respond to the current component characterized by a periodic variation. Also the alternating-current advance clearing-relays are selectively responsive to the current component, having a periodic variation in lieu of a current component of uniform value.

In designating a "uniform or unidirectional current" or "current component" these terms are employed to describe character or condition of a current or current component during any given moment or interval and in contradistinction to a current component which is characterized by a regular or rhythmic periodic variation or alternation—that is to say, the terms are employed to designate a current or current component which is unidirectional or substantially uniform during its employment to maintain some given condition of the traffic controlling or signaling apparatus which it covers. It is to be understood, however, that these terms do not preclude the employment of a weak uniform current to perform a given operation, such as clearing a home signal, and the subsequent movement of a stronger uniform current to perform another operation, such as clearing a distant signal; nor do these terms preclude the employment of unidirectional current of one polarity to perform one of such operations and the subsequent employment of another unidirectional current of the opposite polarity to perform the second of such operations. In such cases the current of lesser strength for performing one operation, the current of greater strength employed to perform another operation, the current of one polarity to perform one operation, and the current of

opposite polarity performing a subsequent operation are each substantially uniform and unidirectional within the meaning of these terms as employed by me.

In the illustrated embodiment of my invention two substantially uniform currents are employed successively to clear the home and the distant signals of a given signaling apparatus, each current being substantially uniform and unidirectional, so long as it is maintained, but the second current having a polarity different from the first current.

It is apparent that my invention may be embodied in various modifications of that embodiment which I have illustrated and particularly described, all such other embodiments coming, however, within the principles and scope of my invention.

What I claim, and desire to secure by Letters Patent, is—

1. A railway traffic-controlling system comprising a traffic-controlling electric circuit, means for supplying the controlling-circuit with a composite electric current including a current component having a given periodic variation, an electrically-controllable railway traffic-controlling apparatus located at a given point on the railway-line and controllable by the controlling-circuit and by its current component having the given periodic variation, and another electrically-controllable railway traffic-controlling apparatus located at a point on the railway-line distant from the first-mentioned traffic-controlling apparatus and likewise arranged in controllable relation to the controlling-circuit but controllable by another component of its composite current.

2. A railway block signaling system comprising a signaling-circuit including the traffic rails of a block or section of the railway-line, means for supplying the signaling-circuit with a composite electric current including a current component having a given periodic variation, an electrically-controllable signaling apparatus located at one end of the railway-block and controllable by the signaling-circuit and by its current component having the given periodic variation, and a second electrically-controllable signaling apparatus located at the other end of the block also in controllable relation to the signaling-circuit but controllable by another component of its composite electric current.

3. A railway traffic-controlling system comprising an electric traffic-controlling circuit extending along the line of traffic of a railway, a source of electric current characterized by a given periodic variation located at a given point on the railway-line and arranged to supply such current to the controlling-circuit, a second source of electric current having a characteristic different from the given periodic variation and arranged to supply such different current to the traffic-

controlling circuit but located at a point on the railway-line distant from the first-mentioned source of current, a traffic-controlling apparatus located at a point on the railway-line distant from the first-mentioned source of current and controllable by the controlling-circuit and by the current of given periodic variation transmitted through the controlling-circuit in a given direction along the railway-line from such first-mentioned source, and a second traffic-controlling apparatus located on the railway-line at a point distant from the second source of current and controllable by the controlling-circuit and by the current transmitted from such second source to such second traffic-controlling apparatus through the controlling-circuit and along the railway-line in a direction opposite to the said given direction of transmission of the current of given periodic variation.

4. A railway signaling system comprising a signal-controlling electric rail-circuit including the traffic-rails of a section of the railway-line, a source of electric current characterized by a given periodic variation located substantially at one end of the section and arranged to supply such current to the rail-circuit, a signaling apparatus located substantially at the other end of the section and controllable by the rail-circuit and by the current of given periodic variation, a second source of electric current different from the current of given periodic variation and located substantially at the opposite end of the section and arranged to supply such different current to the rail-circuit, and a second signaling apparatus located substantially at the end of the section opposite the second source of current and controllable by the rail-circuit and by the current from such second source.

5. A railway traffic-controlling system comprising an electrically-controllable traffic-controlling apparatus located at a given point on a railway-line and normally in condition to prevent trains from proceeding along such railway-line in advance of such given point and controllable by a controlling electric current characterized by a periodic variation, a traffic-controlling rail-circuit including traffic-rails of the railway extending in rear of the traffic-controlling apparatus and arranged in control of such apparatus, means for supplying to the rail-circuit an electric current characterized by a periodic variation, and means for controlling such current of periodic variation from a controlling-point in rear of the traffic-controlling apparatus to change such apparatus from its aforementioned normal condition.

6. A railway traffic-controlling system comprising an electrically-controllable traffic-controlling apparatus located at a given point on a railway-line and normally in condition to prevent trains from proceeding along such railway-line in advance of such given

point and controllable by a controlling electric current characterized by a periodic variation, a traffic-controlling rail-circuit including traffic-rails of the railway extending in rear of the traffic-controlling apparatus and arranged in control of such apparatus, means for supplying to the rail-circuit an electric current characterized by a periodic variation, and means for controlling such current of periodic variation automatically by approach of a train toward the traffic-controlling apparatus from a point in rear thereof to change such apparatus from its aforementioned normal condition.

7. A railway traffic-controlling system comprising an electrically-controllable traffic-controlling apparatus located at a given point on a railway-line and normally in condition to prevent trains from proceeding along such railway-line in advance of such given point and controllable by a controlling electric current characterized by a periodic variation, a traffic-controlling rail-circuit including traffic-rails of the railway extending in rear of the traffic-controlling apparatus and arranged in control of such apparatus, a source of electric current characterized by a periodic variation located at the rear end of the rail-circuit and arranged to supply such current to such circuit, and means for controlling such current of periodic variation from a controlling-point in rear of the traffic-controlling apparatus to change such apparatus from its aforementioned normal condition.

8. A railway traffic-controlling system comprising an electrically-controllable traffic-controlling apparatus located at a given point on a railway-line and normally in condition to prevent trains from proceeding along such railway-line in advance of such given point and controllable by a controlling electric current characterized by a periodic variation, a traffic-controlling rail-circuit including traffic-rails of the railway extending in rear of the traffic-controlling apparatus and arranged in control of such apparatus, a source of electric current characterized by a periodic variation located at the rear end of the rail-circuit and arranged to supply such current to such circuit, and means for controlling such current of periodic variation automatically by approach of a train toward the traffic-controlling apparatus from a point in rear thereof to change such apparatus from its aforementioned normal condition.

9. A railway signaling system comprising a normal danger-signaling apparatus located at a given point on the railway-line and controllable by an electric current characterized by a periodic variation, a controlling rail-circuit in control of the signaling apparatus and including traffic-rails of the railway extending in rear of the signaling apparatus, means

for supplying to the rail-circuit a current characterized by a periodic variation, and means for controlling such current from a point in rear of the signaling apparatus in order to produce a clear indication of such apparatus.

10. A railway signaling system comprising a normal danger-signaling apparatus located at a given point on the railway-line and controllable by an electric current characterized by a periodic variation, a controlling rail-circuit in control of the signaling apparatus and including traffic-rails of the railway extending in rear of the signaling apparatus, means 15 for supplying to the rail-circuit a current characterized by a periodic variation, and means for controlling such current automatically by approach of a train toward the signaling apparatus from in rear to produce a 20 clear indication in the apparatus.

11. A railway signaling system comprising a normal danger-signaling apparatus located at a given point on the railway-line and controllable by an electric current characterized 25 by a periodic variation, a controlling rail-circuit in control of the signaling apparatus and including traffic-rails of the railway extending in rear of the signaling apparatus, a source of electric current characterized by a 30 periodic variation located substantially at the rear end of the rail-circuit and arranged to supply such current to such circuit, and means for controlling such current from a point in rear of the signaling apparatus in 35 order to produce a clear indication of such apparatus.

12. A railway traffic - controlling system comprising an electrically-controllable traffic-controlling apparatus located on a railway-line, and normally in condition to prevent continuance of trains along such railway-line and controllable by an electric-current component having a distinguishing characteristic, means for supplying an electric-current component having the distinguishing characteristic, a traffic-controlling electric circuit in control of the traffic-controlling apparatus and extending therefrom rearward along the railway-line and arranged 45 to conduct the current component having the distinguishing characteristic but also subjected to another current component different in character, and means for controlling the current component having the distinguishing characteristic whereby to effect a given clearing operation of the traffic-controlling apparatus, such traffic-controlling apparatus being selectively controllable by such current component to perform such given 50 clearing operation and being not responsive to the other different current component to perform such given operation.

13. A railway traffic - controlling system comprising an electrically-controllable rail-way traffic-controlling apparatus located on 55

a railway-line and normally blocking traffic on such railway-line, means for supplying an electric-current component characterized by a given periodic variation, a traffic-controlling electric circuit in control of the traffic-controlling apparatus and extending therefrom rearward along the line of railway traffic and arranged to conduct the current component having the given periodic variation but also subjected to the flow of another different current component, and means for controlling the current having the given periodic variation from a point in rear of the traffic-controlling apparatus to control such traffic-controlling apparatus, such traffic-controlling apparatus being selectively responsive to such current having the given periodic variation to perform a given clearing traffic-controlling operation but being not thus responsive to the other different current component.

14. A railway traffic - controlling system comprising an electrically-controllable railway traffic-controlling apparatus located on a railway-line and normally blocking traffic on such railway - line, means for supplying an electric-current component characterized by a given periodic variation, a traffic-controlling electric circuit in control of the traffic-controlling apparatus and extending therefrom rearward along the line of railway traffic and arranged to conduct the current component having the given periodic variation but also subjected to the flow of a uniform current component, and means for controlling the current having the given periodic variation from a point in rear of the traffic-controlling apparatus to control such traffic-controlling apparatus, such traffic-controlling apparatus being selectively controllable by such current having the given periodic variation to perform a given clearing traffic-controlling operation but being not thus responsive to the uniform current component.

15. A railway traffic - controlling system comprising an electrically - controllable traffic-controlling apparatus located on a railway-line and normally blocking traffic on such railway-line, means for supplying an electric-current component characterized by a periodic variation, a rail-circuit in control of the traffic-controlling apparatus and including the traffic-rails of the railway extending in rear thereof and arranged to conduct the current component having the periodic variation but also subjected to flow of a non-periodic current, and means for controlling the current component having the periodic variation by approach of a train toward the traffic-controlling apparatus from in rear thereof whereby to control such traffic-controlling apparatus, such apparatus being selectively responsive to the current component characterized by the periodic variation and controllable thereby to perform a given clearing op- 125 130

eration and being not controllable by the non-periodic current to perform such operation.

16. A railway traffic-controlling system comprising an electrically controllable traffic-controlling apparatus located on a railway-line and normally blocking traffic on such railway-line, means for supplying an alternating electric current, a traffic-controlling rail-circuit arranged in control of the traffic-controlling apparatus and including the traffic-rails of the railway-line extending in rear thereof and communicating with the source of alternating current but subjected also to a non-fluctuating electric current, and means for controlling the alternating-current component in the rail-circuit from a point in rear of the traffic-controlling apparatus to control such apparatus, such apparatus being controllable by such alternating-current component to perform a given clearing operation and not being controllable to perform such operation by the non-fluctuating current component in the rail-circuit.

17. A railway signaling system comprising a signal-controlling rail-circuit including the traffic-rails of a section of the railway-track, a source of electric current characterized by a given periodic variation located substantially at the rear end of the section and arranged to supply such current to the rail-circuit, a second source of electric current having a characteristic different from the given periodic variation and located substantially at the advance end of the section and arranged to supply such different current to the rail-circuit, a signaling apparatus located substantially at the advance end of the section and controllable by the rail-circuit and by its current having the given periodic variation, and a second signaling apparatus located substantially at the rear end of the section and controllable by the rail-circuit and by the different current delivered by the second source of current.

18. A railway traffic-controlling system comprising a traffic-controlling electric circuit extending between two points on the line of traffic of a railway, means for supplying the traffic-controlling circuit with a composite electric current including a component having a periodic variation and a substantially uniform component, a railway traffic-controlling apparatus located at one of the two points on the line of traffic and controllable by the traffic-controlling circuit and by its current component having the periodic variation, a second traffic-controlling apparatus located at the other point on the line of traffic and also controllable by the traffic-controlling circuit but by its substantially uniform current component, and means for controlling the components of the composite current to control the traffic-controlling apparatuses.

19. A railway traffic-controlling system 65 comprising a traffic-controlling electric circuit extending from a given point on a railway-line to a second point distant from the given point, a source of electric current having a periodic variation located at the given 70 point on the railway-line and arranged to supply such current to the controlling-circuit, a traffic-controlling apparatus located at the second point and controllable by the controlling-circuit and by the current of periodic 75 variation, a source of substantially uniform electric current located at such second point on the railway-line and arranged to supply such substantially uniform current to the controlling-circuit, another traffic-controlling apparatus located at the given point on the railway-line and controllable by the controlling-circuit and by its substantially uniform current component, and means for controlling the component having a periodic variation and the substantially uniform component, to control the traffic-controlling apparatuses.

20. A railway signaling system comprising a signal-controlling rail-circuit including traffic-rails of a section of the railway, a source of signal-controlling electric current characterized by a periodic variation located substantially at one end of the railway-section and arranged to deliver its current to the rail-circuit, a signaling apparatus located substantially at the opposite end of the section and controllable by the rail-circuit and by the current of periodic variation, a source of substantially uniform signal-controlling 90 current located substantially at such opposite end of the section and arranged to deliver its current to the rail-circuit, a second railway signaling apparatus located substantially at the first-mentioned end of the section and controllable by the rail-circuit and by its substantially uniform current component, and means for controlling the current component characterized by a periodic variation and the substantially uniform current 95 component, to control the signaling apparatuses.

21. A railway signaling system comprising a signal-controlling rail-circuit including traffic-rails of a section of the railway, a 115 source of substantially uniform signaling current communicating with the rail-circuit substantially at the advance end of the section, a signaling apparatus at the rear end of the section controllable by the rail-circuit and by its substantially uniform signaling-current component, a source of signaling-current having a periodic variation communicating with the rail-circuit at the rear end of the section, a signaling apparatus at the advance 120 end of the section controllable by the rail-circuit and by its signaling-current component having a periodic variation, and means 125

for controlling such current component of periodic variation from a point in rear of the section.

22. A railway signaling system comprising a signal-controlling rail-circuit including traffic-rails of a section of the railway, a source of substantially uniform signaling-current communicating with the rail-circuit substantially at the advance end of the section, a signaling apparatus at the rear end of the section controllable by the rail-circuit and by its substantially uniform signaling-current component, a source of signaling-current having a periodic variation communicating with the rail-circuit at the rear end of the section, a signaling apparatus at the advance end of the section controllable by the rail-circuit and by its signaling-current component having a periodic variation, means for controlling such current component of periodic variation from a point in rear of the section, and means for controlling the substantially uniform signaling-current component from a point in advance of the section.

23. A normal danger railway block-signaling system comprising a signaling rail-circuit including the traffic-rails of a signaling-block of the railway, a source of substantially uniform electric current arranged to supply a substantially uniform current component to the rail-circuit at the advance end of the block, a signaling apparatus at the rear end of the block controllable by the rail-circuit and by its uniform current component, a source of electric current characterized by a periodic variation arranged to supply such a current component to the rail-circuit at the rear end of the block, a signaling apparatus at the advance end of the block controllable by the rail-circuit and by its current component of periodic variation, and a second signaling-circuit including traffic-rails of the railway extending in rear of the block and controlling the current component of periodic variation in the first-mentioned rail-circuit to control the signaling apparatus at the advance end of the block.

24. A normal danger railway block-signaling system comprising a signaling rail-circuit including traffic-rails of a signaling-block of the railway-track, a source of a signal-controlling substantially uniform current component arranged to supply such current component to the rail-circuit at the advance end of the block, a source of another signal-controlling current component characterized by a periodic variation arranged to supply such current component to the rail-circuit at the rear end of the block, a signaling apparatus at the end of the block controllable by the rail-circuit and controllable by selective responsiveness to its current component of periodic variation to perform one operation and controllable to perform another operation by responsiveness to the substan-

tially uniform current component, a second signaling apparatus at the rear end of the block controllable by the rail-circuit and by its uniform current component, a second signal-controlling circuit including traffic-rails of the railway extending in rear of the block and arranged to control the current component of periodic variation in the first-mentioned rail-circuit to effect the first-mentioned operation of the first-mentioned signaling apparatus at the advance end of the block, the substantially uniform current component being controllable by presence of a train in the block to effect the second-mentioned operation of such first-mentioned signaling apparatus.

25. A normal danger home and distant railway block-signaling system comprising signal-controlling rail-circuits extending through the various signaling-blocks and including the traffic-rails thereof, means for supplying to the rail-circuits a signal-controlling current characterized by a periodic variation, signaling apparatuses located at the termini of adjacent blocks and each including a home-signal controllable by the signal-controlling rail-circuit of the block next in advance and each signaling apparatus including also a distant signal, for each distant signal a controlling-circuit controllable by the rail-circuit of the block second in advance when placed in controllable relation to such second advance rail-circuit, each signaling apparatus being responsive to the current component of periodic variation in the signal-controlling circuit extending through the block next in rear to place the controlling-circuit of the next rear distant signal in controllable relation to the next advance rail-circuit, and each signaling apparatus being also controllable by presence of a train in the next rear block to control the current of periodic variation in the next advance block and thus operate the next advance signaling apparatus to place its first advance rail-circuit in control of the distant signal next in rear of such last-mentioned signaling apparatus.

26. A normal danger home and distant railway block-signaling system comprising signal-controlling rail-circuits including the traffic-rails of the various signaling-blocks of the railway, and home and distant railway-signaling apparatuses at the termini of successive blocks each including a source of signal-controlling current having a periodic variation arranged to supply the rail-circuit in advance, a source of non-periodic signal-controlling current arranged to supply the rail-circuit in rear, home-signal clearing means controllable jointly by the non-periodic current component of the rail-circuit in advance and by signal-controlling current in the next rear rail-circuit, means jointly controllable by such non-periodic current component of the next advance rail-circuit and by the cur-

rent component of periodic variation in the next rear rail-circuit to effect a distant-signal-clearing variation in the non-periodic current component of such next rear distant signal, and means for clearing the local distant signal controllable by the non-periodic current component of the next rear rail-circuit to control the current component of periodic variation in the next advance rail-circuit and thus operate the next advance signaling apparatus to effect the distant-signal-clearing change in the non-periodic current component of such next advance rail-circuit to clear the local distant signal at the rear end thereof.

27. A normal danger home and distant railway block-signaling system comprising signaling rail-circuits including the traffic-rails of the various signaling-blocks, and home and distant railway signaling apparatuses located substantially at the termini of successive signaling-blocks and each including a source of signal-controlling alternating current arranged to supply the rail-circuit of the block next in advance, a battery arranged to supply signal-controlling current to the rail-circuit of the next rear block, home-signal-clearing means controllable jointly by the battery-current in the next advance rail-circuit and by one component of the signal-current in the next rear rail-circuit, current-reversing means controllable jointly by such a battery-current of the next advance rail-circuit and by the alternating current component of the next rear rail-circuit and arranged to reverse the battery-current in such next rear rail-circuit, local distant-signal-clearing means responsive to reversal of battery-current in the next advance rail-circuit, and current-controlling means controllable by the battery-current in the rail-circuit of the next rear block and responsive to presence of a train therein to establish flow of alternating current from the source thereof through the next advance rail-circuit to operate the next advance signaling apparatus to reverse the battery-current in such next advance rail-circuit and clear the local distant signal at the rear end thereof.

28. A railway traffic-controlling system comprising a traffic-controlling electric circuit extending from a given point on a railway-line to a second point on the railway-line distant from the given point, means for supplying the traffic-controlling electric circuit with a composite electric current including differently-characterized current components, a traffic-controlling apparatus at the first-mentioned point controllable by the traffic-controlling electric circuit and by one component of its composite current, a second traffic-controlling apparatus located at the distant point and also controllable by the traffic-controlling circuit but controllable by another component of its composite cur-

rent, and means for controlling the components of the composite traffic-controlling current to control the traffic-controlling apparatuses.

29. A railway traffic-controlling system comprising a traffic-controlling electric circuit extending from one point on a railway-line to a second point on the railway-line distant from the first point, a source of one electric current component located at the first point and arranged to supply such current component to the traffic-controlling circuit, a source of a current component of different character located at the second point and arranged to supply such different current component to the traffic-controlling circuit, a traffic-controlling apparatus located at the second point and controllable by the traffic-controlling electric circuit and by the current component delivered by the source of current at the first point, another traffic-controlling apparatus located at such first point and controllable by the traffic-controlling circuit and by the current component delivered by the source of current at the second point, and means for controlling the components of the composite current to control the traffic-controlling apparatuses.

30. A railway traffic-controlling system comprising an electric traffic-controlling rail-circuit including the traffic-rails of a section of the railway, means for supplying to the rail-circuit a composite electric traffic-controlling current including the components of different character, a traffic-controlling apparatus located at one end of the section and controllable by the rail-circuit and by one component of its composite current, a second traffic-controlling apparatus located at the opposite end of the section and also controllable by the traffic-controlling circuit but by a different component of its composite current, and means for controlling the components of the composite current to control the traffic-controlling apparatuses.

31. A railway traffic-controlling system comprising a source of electric current located at one point on a railway-line and arranged to supply its current to the traffic-rails thereof, a second source of electric current of different character located at a second point on the railway distant from the first point but likewise arranged to supply its current to the traffic-rails, an electrically-controllable traffic-controlling apparatus located on the railway-line at a point distant in one direction from the first-mentioned source of current and electrically controllable by the traffic-rails and by the current component from such first source transmitted through such rails in such direction, a second electrically-controllable traffic-controlling apparatus located at a point on the railway distant in the opposite direction from the second source of current and electrically controllable

by the traffic-rails and by the current component of different character transmitted from such second source in such opposite direction through the traffic-rails and to the second traffic-controlling apparatus, and means for controlling the current components to control the traffic-controlling apparatuses.

32. A railway traffic-controlling system comprising a traffic-controlling rail-circuit including the traffic-rails of a section of the railway, a source of traffic-controlling electric current arranged to supply such current to the rail-circuit at the advance end of the section, a traffic-controlling apparatus located at the rear end of the section and controllable by the rail-circuit and by its current component transmitted from the source of current at the advance end of the section, a second source of electric current different in character from the current of the first-mentioned source and arranged to supply such different current to the rail-circuit at the rear end of the section, a second traffic-controlling apparatus located at the advance end of the block and controllable by the rail-circuit and by the second different current component transmitted from the second source of current at the rear end of the section, and means for controlling the second current component from a point on the railway-line in rear of the section.

33. A normal danger home and distant railway block-signaling system comprising signaling rail-circuits including the traffic-rails of the various signaling-blocks of the system, and electrically-controllable home and distant railway signaling apparatuses located at the termini of successive signaling-blocks and each including a source of signaling-current of definite character arranged to supply the rail-circuit of the next block in rear, a second source of signaling-current of second or different character arranged to supply the rail-circuit of the block next in advance, home-signal-clearing means controllable jointly by the signaling-current component of first or definite character transmitted through the next advance rail-circuit and by one signaling-current component of the next rear rail-circuit, means jointly controllable by such current component of first character in the next advance rail-circuit and by the second or different current component in the next rear rail-circuit and arranged to effect a distant-signal-clearing change in the current component of first character in the next rear rail-circuit, and local distant-signal-clearing means controllable by the current component of first character in the next rear rail-circuit to control the current component of second character in the next advance rail-circuit and thus operate the next advance signaling apparatus to effect the distant-signal-clearing change in the current of first character in

such next advance rail-circuit and thereby clear the distant signal at the rear end thereof. 65

34. A railway traffic-controlling system comprising a traffic-controlling electric circuit, means for supplying the controlling-circuit with a composite electric current including a current component having a given periodic alternation, an electrically-controllable railway traffic-controlling apparatus located at a given point on the railway-line and controllable by the controlling-circuit and by its current component having the given periodic alternation, and another electrically-controllable railway traffic-controlling apparatus located at a point on the railway-line distant from the first-mentioned traffic-controlling apparatus and likewise arranged in controllable relation to the controlling-circuit but controllable by another component of its composite current. 80

35. A railway block-signaling system comprising a signaling-circuit including the traffic-rails of a block or section of the railway-line, means for supplying the signaling-circuit with a composite electric current including a current component having a given periodic alternation, an electrically-controllable signaling apparatus located at one end of the railway-block and controllable by the signaling-circuit and by its current component having the given periodic alternation, and a second electrically-controllable signaling apparatus located at the other end of the block also in controllable relation to the signaling-circuit but controllable by another component of its composite electric current. 95

36. A railway signaling system comprising a signal-controlling electric rail-circuit including the traffic-rails of a section of the railway-line, a source of electric current characterized by a given periodic alternation located substantially at one end of the section and arranged to supply such current to the rail-circuit, a signaling apparatus located substantially at the other end of the section and controllable by the rail-circuit and by the current of given periodic alternation, a second source of electric current different from the current of given periodic alternation and located substantially at the opposite end of the section and arranged to supply such different current to the rail-circuit, and a second signaling apparatus located substantially at the end of the section opposite the second source of current and controllable by the rail-circuit and by the current from such second source. 110

37. A railway traffic-controlling system comprising an electrically-controllable traffic-controlling apparatus located at a given point on a railway-line and normally in condition to prevent continuance of railway-trains along a given track beyond such given point and controllable by a controlling alter- 125

nating current of electricity, a traffic-controlling rail-circuit including traffic-rails of the railway extending in rear of the traffic-controlling apparatus and arranged in control of such apparatus, means for supplying to the rail-circuit an alternating electric current, and means for controlling such alternating current from a controlling-point in rear of the traffic-controlling apparatus to reverse the aforementioned normal condition of such apparatus.

38. A railway traffic-controlling system comprising an electrically-controllable traffic-controlling apparatus located at a given point on a railway-line and normally in condition to prevent continuance of railway-trains along a given track beyond such given point and controllable by a controlling alternating current of electricity, a traffic-controlling rail-circuit including traffic-rails of the railway extending in rear of the traffic-controlling apparatus and arranged in control of such apparatus, means for supplying to the rail-circuit an alternating electric current, and means for controlling such current automatically by approach of a train toward the traffic-controlling apparatus from a point in rear thereof to reverse the aforementioned normal condition of such apparatus.

39. A railway traffic-controlling system comprising an electrically-controllable traffic-controlling apparatus located at a given point on a railway-line and normally in condition to prevent continuance of railway-trains along a given track beyond such given point and controllable by a controlling electric alternating current, a traffic-controlling rail-circuit including traffic-rails of the railway extending in rear of the traffic-controlling apparatus and arranged in control of such apparatus, a source of electric alternating current located at the rear end of the rail-circuit and arranged to supply such current to such circuit, and means for controlling such alternating current from a controlling-point in rear of the traffic-controlling apparatus to reverse the aforementioned normal condition of such apparatus.

40. A railway signaling system comprising a normal danger-signaling apparatus located at a given point on the railway-line and controllable by an electric alternating current, a controlling rail-circuit in control of the signaling apparatus and including traffic-rails of the railway extending in rear of the signaling apparatus, means for supplying to the rail-circuit an alternating current, and means for controlling such current from a point in rear of the signaling apparatus to clear the signal.

41. A railway signaling system comprising a normal danger-signaling apparatus located at a given point on the railway-line and controllable by an alternating electric current, a controlling rail-circuit in control of the sig-

naling apparatus and including traffic-rails of the railway extending in rear of the signaling apparatus, means for supplying an alternating current to the rail-circuit, and means for controlling such current automatically by approach of a train toward the signaling apparatus from in rear to clear the signal.

42. A railway signaling system comprising a normal danger-signaling apparatus located at a given point on the railway-line and controllable by an electric alternating current, a controlling rail-circuit in control of the signaling apparatus and including traffic-rails of the railway extending in rear of the signaling apparatus, a source of alternating electric current located substantially at the rear end of the rail-circuit and arranged to supply such current to such circuit, and means for controlling such current from a point in rear of the signaling apparatus in order to clear the signal.

43. A railway traffic-controlling system comprising an electrically-controllable traffic-controlling apparatus located on a railway-line, means for supplying an electric current component having a distinguishing characteristic, a traffic-controlling electric circuit in control of the traffic-controlling apparatus and extending therefrom rearward along the railway-line and arranged to conduct the current component having the distinguishing characteristic but also subjected to another current component different in character, and means for controlling the current component having the distinguishing characteristic whereby to control a given operation of the traffic-controlling apparatus, such traffic-controlling apparatus being selectively responsive to such current component to perform such given operation and being responsive to the other different current component to perform another operation.

44. A railway traffic-controlling system comprising an electrically-controllable railway traffic-controlling apparatus located on a railway-line and normally in condition to prevent continuance of trains along a given track of the railway-line, means for supplying an electric current component characterized by a given periodic alternation, a traffic-controlling electric circuit in control of the traffic-controlling apparatus and extending therefrom rearward along the line of railway traffic and arranged to conduct the current component having the given periodic alternation but also subjected to the flow of another different current component, and means for controlling the current component having the given periodic alternation from a point in rear of the traffic-controlling apparatus to control such traffic-controlling apparatus, such traffic-controlling apparatus being selectively responsive to such current component having the given periodic alter-

nation to reverse the aforementioned normal condition but being not thus responsive to the other different current component.

45. A railway traffic-controlling system comprising an electrically-controllable railway traffic-controlling apparatus located on a railway-line, means for supplying an electric current component characterized by a given periodic variation, a traffic-controlling electric circuit in control of the traffic-controlling apparatus and extending therefrom rearward along the line of railway traffic and arranged to conduct the current component having the given periodic variation, but also subjected to the flow of another different current component, and means for controlling the current having the given periodic variation from a point in rear of the traffic-controlling apparatus to control such traffic-controlling apparatus, such traffic-controlling apparatus being selectively responsive to such current having the given periodic variation to perform a given traffic-controlling operation and being also responsive to the other different current component to perform another operation.

46. A railway traffic-controlling system comprising an electrically-controllable railway traffic-controlling apparatus located on a railway-line and normally in condition to prevent continuance of trains along a given track of the railway-line, means for supplying an electric current component characterized by a given periodic alternation, a traffic-controlling electric circuit in control of the traffic-controlling apparatus and extending therefrom rearward along the line of railway traffic and arranged to conduct the current component having the given periodic alternation but also subjected to the flow of a uniform current component, and means for controlling the current having the given periodic alternation from a point in rear of the traffic-controlling apparatus to control such traffic-controlling apparatus, such traffic-controlling apparatus being selectively controllable by such current having the given periodic alternation to permit continuance of trains along the given railway-track but being not thus responsive to the uniform current component.

47. A railway traffic-controlling system comprising an electrically-controllable railway traffic-controlling apparatus located on a railway-line, means for supplying an electric current component characterized by a given periodic variation, a traffic-controlling electric circuit in control of the traffic-controlling apparatus and extending therefrom rearward along the line of railway traffic and arranged to conduct the current component having the given periodic variation but also subjected to the flow of a uniform current component, and means for controlling the current having the given periodic variation from a point in rear of the traffic-controlling apparatus to control such traffic-controlling apparatus, such traffic-controlling apparatus being selectively responsive to such current having the given periodic variation to perform a given traffic-controlling operation and being also responsive to the uniform current component to perform another operation.

48. A railway traffic-controlling system comprising an electrically-controllable traffic-controlling apparatus located on a railway-line, means for supplying an electric current component characterized by a periodic variation, a rail-circuit in control of the traffic-controlling apparatus and including the traffic-rails of the railway extending in rear thereof and arranged to conduct the current component having the periodic variation but also subjected to flow of a non-periodic current, and means for controlling the current component having the periodic variation by approach of a train toward the traffic-controlling apparatus from in rear thereof whereby to control such traffic-controlling apparatus, such apparatus being selectively responsive to the current component characterized by the periodic variation and controllable thereby to perform a given operation and being controllable by the non-periodic current to perform another operation.

In testimony whereof I have affixed my signature in presence of two witnesses.

CLYDE J. COLEMAN.
